TRAVERSE-MOTION FOR YARN-SPINNING APPARATUS.

1,125,924.

Specification of Letters Patent.

Patented Jan. 26, 1915.

Application filed May 31, 1913. Serial No. 770,865.

To all whom it may concern:

Be it known that I, LOUIS S. BURBANK, a citizen of the United States, residing at Hopedale, county of Worcester, State of Massachusetts, have invented an Improvement in Traverse-Motions for Yarn-Spinning Apparatus, of which the following description, in connection with the accompanying drawing, is a specification, like characters on the drawing representing like parts.

This invention relates to a traverse motion for yarn spinning apparatus of that type wherein a primary winding or bunch 15 is first wound or spun upon the bobbin or yarn carrier and thereafter a secondary or main winding of the yarn is laid upon the yarn carrier to complete the building of the yarn mass thereon.

20 Yarn carriers on which the yarn is wound in this way to provide a primary winding or "bunch" are designed for use in automatic weft-replenishing looms wherein the 15 woven off to a predetermined extent is effected through the instrumentality of a feeler.

The primary winding or bunch contains a sufficient quantity of yarn to maintain 30 continuity of filling when the filling-replenishing operation is effected.

The objects of the present invention are to provide a novel mechanism for building the bunch on a yarn carrier which can be 35 easily applied to any spinning frame without requiring special parts, and further to provide a bunch builder of this type which is adapted to wind the bunch on the yarn carrier in such a form that the yarn will 40 draw off therefrom freely during weaving and without danger of breaking; and further to provide a bunch-building mechanism of this type constructed so that the length and the shape of the bunch as well as the 45 number of traverses put into the bunch and the position of the bunch on the bobbin or yarn carrier can be adjusted to suit the requirements of use. By means of my mechanism it is possible, therefore, to wind a 50 bunch of the size, shape, character and position required for any particular feeler loom.

In order to provide a bunch-building

mechanism which can be used in connection with any spinning frame, I have devised a 55 bunch-building mechanism which is associated with and operated by the builder chain of the usual builder mechanism, so that a spinning frame can be equipped with my bunch-building mechanism merely by attaching the latter to the frame of the machine and then passing the builder chain of the usual builder mechanism through my apparatus.

My improved bunch building mechanism 65 is so constructed that during the operation of winding the bunch it operates to absorb part of the motion given to the builder chain by the builder arm so that only a portion of this motion will be transmitted 70 to the ring rail. This causes the ring rail to have a short traverse which results in winding the bunch on the yarn carrier. This absorption of part of the motion given to the builder chain is provided for by forming a loop in the builder chain and employing mechanism for lengthening and shortening the loop as the chain reciprocates, the lengthening of the loop absorbing part of 75 the motion given to the builder chain. 80

My improved bunch builder mechanism is also provided with means whereby after the bunch is formed it becomes automatically inoperative thereby permitting all of the motion given to the builder chain to be 85 transmitted to the ring rail, this being the condition that exists during the laying of the winding. My bunch builder mechanism is provided with adjustments which provide for varying the size, shape and position of 90 the bunch on the yarn carrier.

My invention also comprehends means whereby the traverse of the ring rail is shortened just before the bobbin is completely wound, so that a mass of yarn which 95 is laid with the short traverse will be wound on the tip of the bobbin. The advantage of this is that a larger amount of yarn can be wound on the bobbin and the final winding on the tip of the bobbin acts as a means to 100 hold the yarn mass solidly in place.

Referring to the drawings wherein I have illustrated a selected embodiment of my invention which is sufficient to show the principle thereof, Figure 1 is a front elevation 105 of a portion of a spinning frame with my

improvements applied thereto; Fig. 2 is an enlarged front view of my improved bunch builder mechanism; Fig. 3 is a similar view looking from the opposite side; Fig. 4 is a top plan view; Fig. 5 is a sectional view; Fig. 6 is a sectional view on substantially the line $x-x$, Fig. 3; Fig. 7 is a side elevation of the builder motion; Fig. 8 is a diagrammatic view showing the principle of 10 operation of my bunch-building mechanism; Fig. 9 is a view similar to Fig. 2, but showing the parts in a different position; Fig. 10 shows a bobbin or yarn carrier which has been wound by means of the herein-described invention; Fig. 11 is a section on substantially the line $y-y$, Fig. 6.

1 designates the girder or ladder of the main frame, the portion 2 of which constitutes the spindle rail in which are mounted 20 the usual spindles 3 adapted to receive bobbins or yarn carriers 4, and 5 is the usual ring rail provided with the spinning rings 6. This ring rail is supported by the lifter rods 7 which are connected to the rocking 25 arms 8 pivoted at 9 and having integral therewith the upturned arms 10 carrying the segment 11 to which the builder chain 12 is secured. This builder chain leads to the winding drum 13 rotatably mounted 30 upon the builder arm 14 which is pivoted at 15 and which carries the worm 16 that engages with the worm teeth formed on the gear 17 that is rigid with the winding drum 13. The shaft 18 of the worm 16 has the 35 ratchet or pick wheel 19 thereon which is actuated by the pick pawl 20 in usual fashion. 21 designates the traverse cam which operates to reciprocate the builder arm 14. The parts thus far described are or may be 40 all as usual in builder or traverse motions of yarn spinning machines, and form no part of my present invention.

The cam 21, it will be understood, is so constructed that it gives a vibrating movement of constant stroke to the builder arm 14 which, if transmitted to the ring rail, would cause a traverse of uniform length of the yarn on the bobbin. As the winding proceeds the pick pawl operates to gradually turn the winding drum 13, as will be 45 readily understood by those who are familiar with the art, thereby causing a gradual lengthening of the builder chain 12 and a consequent gradual rise in the ring rail 5. 50 This is commonly referred to as the "gain" which is given to the traverse motion as the winding proceeds. As stated above, my invention aims to provide a bunch-building mechanism which can be applied to a spinning 55 frame of the type above described without requiring any specially constructed parts in the builder motion, and my invention, therefore, makes it possible to apply a bunch-building mechanism to any spinning 60 frame without the necessity of rebuilding 65

entirely or in part the traverse motion of said machine.

The principle on which my invention operates can perhaps best be seen from Fig. 8, in which 12 designates the builder chain 70 which has a loop 22 formed therein, said loop passing around a sprocket wheel 23 rotatable about the center 39. Associated with the sprocket wheel 23 is a bunch building cam 25 adapted to engage a roll 26 that is 75 mounted in fixed bearings.

Assuming that the bunch-building cam 25 is secured to the sprocket wheel 23 to rotate therewith it will be readily seen that as the builder chain moves back and forth during 80 the vibrating movement of the builder arm 14, such back and forth movement will cause the sprocket wheel 13 to oscillate. This oscillating movement causes the bunch-building cam 25 to ride over the stationary roll 85 26. The face 56 of this bunch-building cam is eccentric relative to the sprocket wheel 23 so that as the sprocket wheel turns in the direction of the arrow a Fig. 8, the engagement 90 of the cam face 56 with the roll 26 will force the bunch-building cam 25 and sprocket wheel 23 bodily downward thereby lengthening the loop 22, while the sprocket wheel is rotated in the opposite direction by the movement of the builder chain, said 95 sprocket wheel will rise thereby shortening the loop 22. So long as the builder cam 25 is in operative engagement with the roll 26, therefore, the back and forth or reciprocating motion of the builder chain 12 will 100 cause a lengthening and shortening of the loop 22, the extent of such lengthening and shortening movement depending upon the contour of the bunch-building cam 25. This cam 25 is so disposed that the loop 22 of the builder chain is lengthened when the builder arm 12 is rising and the builder chain is moving in the direction of the arrow b , while the loop is shortened during 105 the movement of the chain in the opposite direction. It will thus be seen that at each movement of the builder chain 12 in a direction to raise the ring rail the loop 22 is lengthened, while at each movement of the chain in a direction to lower the ring rail 110 the loop is shortened. The extent to which the ring rail 5 is raised and consequently the extent of the traverse at any particular time in the operation of the spinning machine depends upon the amount of motion 115 which is transmitted from the builder chain 12 to the rocker 8, and when the loop 22 in the builder chain is lengthened and shortened, as above described, a part of the motion 120 which is transmitted to the builder chain from the builder arm will be absorbed in the builder chain so that only a portion of the motion of the builder arm will be transmitted to the ring rail. This absorption 125 of part of the motion of the builder arm 130

in the builder chain causes a corresponding shortening of the traverse. This is the operation which is carried out by my invention during the building of the bunch 80 on the bobbin. After the bunch has been wound on the bobbin then the bunch-building cam 25 automatically becomes inoperative, as will be more fully hereinafter described, and during the winding of the main portion 99 of the yarn mass on the bobbin, the sprocket wheel 25 is held from rising and falling movement with the result that the oscillation of said sprocket wheel will not cause any lengthening or shortening of the loop and the entire motion which is given to the builder chain is thus transmitted to the ring rail.

It will thus be seen from the above that my invention provides means for absorbing part of the motion given to the builder chain during the operation of winding the bunch 80 while permitting the full motion of the builder chain to be transmitted to the ring rail during the winding of the main portion 99 of the yarn mass. The preferred mechanism by which this operation of absorbing part of the motion of the builder chain is secured will now be described.

The frame 1 is shown as having secured thereto a supporting bracket 28 on which the bunch-building mechanism is mounted. This bunch-building mechanism is in turn sustained by a frame 29 which has an annular shape and which is formed with two slots 30 in which are adjustably secured supporting arms 31. These arms 31 are in turn sustained by hubs 32 in a plate 33 which is adjustably secured to the supporting bracket 28 by means of clamping bolts 34, said bracket preferably having slots 35 therein to provide of vertical adjustment. The frame 29 sustains two direction pulleys 36 over which the bunch-building chain 12 passes, and it also supports a swinging carrier 37 which is pivoted to the frame at 38 and which carries the sprocket wheel 23 over which the chain passes and the bunch-building cam 25. This swinging carrier 37 sustains a shaft 39 see Fig. 5, on which the sprocket wheel 23 is mounted for rotation. This sprocket wheel is made fast to a hub 40 which is loosely mounted on the shaft 39 and the hub has mounted thereon two disks 41 and 42 between which the bunch-building cam 25 is received. The hub 40 also has clamped thereon a collar 43 provided with an arm 44 which is connected to the disks 41, 42 through a pin 45 that extends transversely through both disks. The end of the arm 44 is forked and is provided with two adjusting screws 46 between which the end of the pin 45 is received, these adjusting screws providing for making a slight angular adjustment of the disks 41, 42 relative to the hub 40. The bunch-building cam 25,

which, it will be remembered, is received between the two disks 41 and 42, is pivotally mounted upon a pin 47 see Fig. 6 carried by said disks, said pin preferably having a bushing 48 thereon which constitutes a spacer for holding the disks 41, 42 apart sufficiently to prevent them from binding on the bunch-building cam, and also constituting a wear bushing for the cam.

The bunch-building cam 25 is acted upon by a spring 49 which tends normally to throw it outwardly into its operative position, as shown in Figs. 2 and 3, but which permits the cam to collapse into its inoperative position, as seen in Fig. 9. One end of this spring 49 is connected to the tail 50 of the bunch-building cam 25, and the other end of the spring is connected to a thrust member 51 which is confined between the two disks 41, 42, and the end 52 of which engages in a notch in the bunch-building cam above the pivotal pin 48. The outer end of the thrust member 51 has bearing against a guide member 53 and the effect of the spring 49 is thus transmitted to the bunch-building cam on both sides of the pivot, said spring acting on the cam in both places with a force tending to turn it in the same direction. As the bunch-building cam swings about its pivot 48, as will be presently described, the thrust member 51 will move up and down along the guide 53. This guide 53 is in the nature of a metal strip which is of a width corresponding to the distance between the disks 41 and 42, and it is sustained at its end 100 on clamping bolts 54 that tie the disks together.

The roll 26 against which the bunch-building cam operates is journaled in a supporting member 55 which is secured to the frame 29.

The normal position of the bunch-building cam at the beginning of the winding of the bunch is that shown in Figs. 2, 3 and 8. The frame 29 is fixed in position so that the roll 26 turns about a fixed axis. It will, therefore, result that as the builder chain 12 moves in the direction of the arrow *b* the sprocket wheel 23 will be turned about its axis thereby turning the disks 41 and 42 and the bunch-building cam 25, said bunch-building cam turning in the direction of the arrow *a*, Figs. 2, 3 and 8. This movement of the cam causes the face 56 thereof to pass over the roll 26, and as the face is eccentric to the axis of the sprocket wheel, such movement forces the sprocket wheel downwardly, as seen by the dotted lines Fig. 8 the frame 37 swinging down about the pivot 38 during this movement. This causes the lengthening of the loop 22 in the builder chain which was above described and the consequent absorption of a portion of the motion of the builder chain, so that only a portion of the complete motion of the chain is transmitted

to the ring rail. When the chain moves in the opposite direction the sprocket wheel 23 and bunch-building cam are turned back into the position shown in Figs. 2 and 3 thereby giving up the length of builder chain which was absorbed in the loom.

The builder chain has two distinct motions as usual in mechanisms of this type, one the back and forth motion which produces the regular traverse motion and the other a gradual outfeed which produces the so-called "gain", this gain or outfeed resulting from the operation of unwinding the builder chain gradually from the winding drum 13. This gain or gradual out-feed of the builder chain will cause a gradual turning movement of the sprocket wheel and bunch-building cam, so that the roll 26 will gradually advance over the cam face 56, and if this operation were continued long enough the sprocket wheel 23 and disks 41, 42 would be turned to such an extent through the gradual outfeed of the builder chain that the bunch-building cam would pass completely out from under the roll 26. This gain is quite slow, however, and as it is necessary to lay only a few traverses in the bunch, I have provided means whereby the movement of the bunch-building cam past the roll 26 is accelerated. To accomplish this end the cam is provided with gear teeth 57 see Fig. 11, which mesh with a pinion 58 carried by a shaft 59 that is journaled at one end in the disk 41, and at the other end in a supporting bracket 60. This shaft 59 has fast thereon a ratchet or pick wheel 61 which is adapted to be engaged by a pick pawl 62 that is slidably mounted in the housing 55. 64 is a stop pawl adapted to engage the pick wheel to prevent backward rotation thereof, said pawl being mounted for turning movement on the hub 65 of the disk 42 and being acted upon by a suitable spring 66. Each time that the sprocket wheel and builder cam turn into the dotted line position shown in Fig. 8 the pick pawl engages the pick wheel and turns the latter thereby swinging the bunch-building cam 25 inwardly, and by this operation said cam is moved inwardly as the sprocket wheel is gradually turned. As a result of these two movements the point 63 of the cam is brought directly under the roll at the end of the predetermined number of traverses necessary to form the desired bunch on the bobbin. At this time it is desirable that the bunch-building cam should be thrown out of further operation, and my invention provides means whereby said cam will be automatically rendered inoperative at the time when the point 63 thereof comes under the roll 26. The manner of pivoting the cam in the disks is such that when the disks 41, 42 are turned into such a position that the point 63 of the cam comes directly under the roll 26, then the pressure of the cam against

the roll due to the strain on the builder chain 12 is in a radial direction and is such as to force the cam down into its inoperative position shown in Fig. 9, such movement being against the action of the spring 49. The stop pawl 64 operates to hold the cam in such position. As the bunch-building cam is thus rendered inoperative, means come into play for locking the swinging support 37 and the shaft 39 in a fixed position during the winding of the remainder of the bobbin, so that the loop 22 in the builder chain will remain of the same length and the full movement given to the builder chain will be transmitted therethrough to the ring rail. This is the condition of the parts during the laying of the main or service winding 99 on the bobbin. The means for thus locking the swinging frame 37 and shaft 39 in their fixed position is as follows: 67 designates a locking pawl which is pivotally mounted to the frame 29 at 68, said pawl having a weighted extension 69 which tends normally to swing the upper end thereof toward the center of the frame. This pawl is provided with a shoulder 70 which at the proper time is adapted to engage over the portion 71 of the swinging frame 37 thereby locking said frame in its lowered position and in a position in which the cam disks 41, 42 will be held out of engagement with the roll 26. The locking pawl 67 has secured thereto a spring arm 72, the upper forked end 73 of which rests against either the portion 71 of the frame 37 or the periphery of the disk 41. As the disks 41, 42 gradually turn in the direction of the arrow A, the notch or low portion 74 in the periphery of the disks is finally brought opposite the portion 73 of the spring arm and when this occurs the latch 67 is swung inwardly by its weight 69 thereby bringing the shoulder 70 into position to engage the portion 71 of the swinging frame 37. During each reciprocation of the builder chain 12 this swinging frame 37 will swing downwardly to bring the point 71 below the level of the shoulder 70 and when during the operation of the device the notch 74 is brought around opposite the portion 73, then at the next downward movement of the frame 37 which is that during which the cam 25 is collapsed, the latch 67 will engage the frame 37 and thus hold it in its lowered position, as seen in Fig. 9. This is the position in which the parts remain while the main or service winding 99 is being wound, and when the parts are in this position the periphery of the disks 41, 42 is slightly below the roll 26. There is, therefore, no friction on the disks and the builder chain and disks have a free oscillating movement.

My invention also provides means whereby when the bobbins have been completely wound and are ready to be doffed, the latch 130

67 will be disengaged from the swinging frame 37, thus allowing the bunch-building mechanism to be again thrown into operative engagement with the roll 26. When 5 the bobbins are filled the ring rail 5 will be near the top of the bobbin but at the bottom of the traverse, and in order to doff the bobbins, the ring rail must be brought to its lowered position. This can be done 10 either by the operator pressing downwardly by his foot on the treadle 75 which is connected to the rocker arm 8 or by turning the winding drum 13 to wind the builder chain 12 thereon. My invention comprehends means whereby when the ring rail 15 is brought into lowered position by either one of these two means, the latch 67 will be disengaged from the swinging frame. It will be remembered that the latch is normally held in its inoperative position shown 20 in Fig. 2 by the engagement of the portion 73 of the spring arm 72 against the periphery of the disk 41. When the disks are turned into a position to bring the notch 25 74 therein opposite the portion 73, then the latch 67 is swung forwardly into its operative position to engage the portion 71 of the swinging frame 37, as above described. During the subsequent turning movement 30 of the disks 41, 42, the inclined portion 76 thereof engages the nose portion 73 of the spring arm 72 and forces the latter backwardly, thus flexing the arm away from the portion 67 as seen by the dotted lines Fig. 35 9. During this time the shoulder 70 of the pawl is engaging the portion 71 of the swinging frame 37, and the frictional engagement between these parts is sufficient to prevent the pawl from being disengaged 40 from the swinging frame when the spring arm 72 is flexed backwardly. This is the position which the parts will maintain during the winding of the main or service portion 99 of the bobbin.

45 When the bobbin is completely wound if the ring rail is lowered by the operator depressing the treadle 75, then such downward movement of the treadle will give slack to the builder chain 12, such slack 50 allowing the swinging frame 37 to drop somewhat thereby relieving the pressure between the shoulder and the part 71 of said swinging frame. As soon as this occurs the resiliency of the spring arm 72 will 55 swing the latch 67 backwardly into the position shown in Fig. 2 so that when the parts are restored to their normal position the building mechanism will be brought against the roll 26. If, on the other hand, 60 the ring rail 5 is depressed into its lowered position by winding up the builder chain on the winding drum 13, then I provide a cam 77 which is adjustably clamped between the two disks 41, 42 and which projects slightly beyond the periphery of the 65 disks, as seen in Fig. 2. This cam is so placed between the disks that it will come around under the roll 26 at the time when the bobbins are substantially wound. As soon as the cam comes into engagement with 70 the roll 26, then the swinging frame 37 will be forced downwardly thereby relieving the frictional pressure between the shoulder 70 and the part 71 and allowing the resiliency of the spring arm 72 to throw 75 the latch 67 into its inoperative position. The cam 77 can be placed in any position around the periphery of the disks 41, 42, depending upon the length of the bobbin desired. This cam 77 is also made use of 80 for laying an auxiliary bunch or traverse of short length on the tip end of the bobbin, as shown at 78 in Fig. 10, for it will be observed that when the disks 41, 42 have been turned into a position so that the cam 85 71 begins to oscillate beneath and in engagement with the roll 26, then during such movement of the builder chain 12 the swinging frame 37 will be lowered and the loop 22 in the builder chain will be lengthened, 90 thus absorbing some of the motion of the builder chain as is done by the formation of the bunch-building cam 25. The traverse is thereby shortened to the extent which the loop is lengthened and a mass 78 of 95 yarn will be laid on the tip of the bobbin with a comparatively short traverse. This yarn mass 78, which I will refer to as the "final" winding, is laid over the tip end of the main or service winding, and it acts 100 to hold the service winding firmly in place and also constitutes an additional yarn mass which increases the total amount of yarn sustained by the yarn carrier. This final winding 78 is applied to the bobbin in such 105 a position that it does not appreciably increase the total length of the yarn mass on the bobbin, but it fills in a space at the tip of the bobbin which would otherwise have no yarn thereon. I believe I am the 110 first to provide means for winding a bobbin with a primary and a final winding both of which are laid with a shorter traverse than the main or service winding. I also believe I am the first to wind any bobbin whether or not it has a primary winding thereon, with a final winding which is wound with a short traverse thereby to provide what constitutes a bunch at the tip 115 of the bobbin.

120 After the winding of the bobbin is completed and the parts are restored to their normal position for beginning the winding of yarn on fresh or unfilled bobbins, then it is necessary that the bunch-building 125 mechanism should be again rendered operative. My invention provides means whereby the bunch-building cam 25 which, it will be remembered has been held in its collapsed or inoperative position during the 130

winding of the main portion of the bobbin, will be automatically thrown into its operative position again when the winding is started on fresh or unfilled bobbins. When 5 the builder chain 12 has been wound up on the drum 13 and the mechanism is ready to begin winding on fresh bobbins, the disks 41, 42 will be brought into substantially the position shown in Figs. 2 and 3. When 10 the spinning frame is started up after the filled bobbins have been doffed and fresh bobbins have been supplied, it is customary for the operator to "jump" the ring rail up and down as the frame starts in order 15 to prevent the ends from breaking, this being accomplished by depressing the treadle 75 slightly with the foot several times. This action of jumping the ring rail is made use of for automatically restoring the 20 bunch-building cam to its operative position.

It will be remembered that the bunch-building cam 25 is prevented from moving outwardly under the influence of the spring 25 49 by the locking pawl 64, and the operation of restoring the bunch-building cam to its operative position consists in releasing the pawl 64 from the ratchet wheel 61, thus 30 allowing the spring 49 to swing said cam outwardly into its operative position. This is accomplished by providing the pawl 64 with a tail 79 which is adapted to engage a stop finger 98 rigidly secured to the frame 29 (see Fig. 3). When the spinning frame 35 is started up and the operator "jumps" the ring rail, this jumping action gives a slight slack to the builder chain 12, thus allowing the swinging frame 37 to swing downwardly somewhat. This downward 40 movement brings the tail 79 of the locking pawl against the stop 98 thereby disengaging the locking pawl from the pick wheel 61. As soon as the pawl is thus disengaged 45 the spring 49 operates to move the bunch-building cam 25 outwardly into its operative position shown in Figs. 2 and 3. The extent of such outward movement is limited by an adjustable stop 81 in the form of a stop screw carried by the frame 29.

50 As stated above my mechanism is constructed so as to permit of a variation in the length, position and shape of the bunch. The length of the primary bunch 80 is determined by the shape of the cam face 56. 55 The steeper the cam face or the more nearly radial said face extends the shorter will be the bunch, while the more nearly said cam face approaches the curvature of the disks 41, 42, the longer will be the bunch. This 60 will be evident when it is remembered that at each reciprocation of the builder arm the builder chain 12 moves back and forth through a definite distance, and when it is observed that the steeper or more nearly 65 radial the face 56 of the bunch-building

cam is the greater will be the downward and upward movement of the frame 37 at each reciprocation of the builder chain. This up and down movement of the frame 37 results in shortening or lengthening the 70 loop thereby to absorb in the builder chain a portion of the motion given thereto. The more of the motion of the builder chain which is given up in lengthening the loop the less will be the proportion of the motion 75 transmitted to the ring rail, and hence the shorter the traverse. Therefore, it will be seen, that by making the face 56 of the builder cam steep a short traverse will be given during the winding of the primary 80 bunch 80, thus making a short bunch, while by giving the face 56 a less angle the bunch 80 will be correspondingly lengthened.

In building a primary bunch 80 it is desirable that the rear end 83 of the bunch 85 should have a gradual incline so that when the yarn which is wound at the rear of the bunch is being drawn off from the bobbin there will be no danger of said yarn catching on the bunch and thus becoming broken. I secure this desirable shape to the bunch 90 80 by giving the cam face 56 a special contour, said face being made so as to give a more rapid movement to the traverse of the ring rail when the rear portion 83 of 95 the bunch is being wound than when the front portion thereof is being wound. This causes the bunch to be built with the inclined rear portion which will offer no obstruction to the free drawing off of the 100 yarn from the bobbin.

It is of advantage to build the bunch a slight distance from the butt of the bobbin and then to wind the main winding so as to entirely cover the bunch and fill the portion of the bobbin between the bunch and the butt thereof, for this enables a larger quantity of yarn to be wound on the bobbin than would be possible where the bunch is situated entirely outside of the main or 110 service winding.

The position of the bunch from the butt of the bobbin is determined by the distance which the bunch-building cam is allowed to stand out beyond the disks 41, 42, and this 115 in turn is determined by the stop screw 81. If the bunch is to be built down close to the butt of the bobbin, then the cam 25 is allowed to have its extreme outward position, while if the bunch is to be built at a 120 slight distance away from the butt of the bobbin, then the set-screw 81 will be adjusted inwardly so as to limit the extent to which the bunch cam can move outwardly when it is released.

125 Another advantage which is inherent in my construction is that my improved bunch builder can be put on either a right hand or a left hand frame, that is, the same parts can be assembled so as to fit either a right hand 130

or a left hand frame without the requiring of any additional parts for this purpose.

Another advantage which is inherent in my bunch builder is that it can be applied 5 to any spinning frame now in use without requiring any alteration in the ordinary builder mechanism, for the bunch builder is entirely separate from the usual builder arm. The only change which would be required 10 would be to substitute for the builder chain in use on an ordinary frame another builder chain which was sufficiently long to permit of the loops being formed therein.

I regard it as novel to provide a bunch-building mechanism which coöperates with the builder chain intermediate of its ends and which acts to absorb or take up in the builder chain a portion of the movement given thereto by the builder arm so that 20 only a portion of such movement will be transmitted to the ring rail, and I desire to claim this feature broadly.

Having fully described my invention, what I claim as new and desire to secure by 25 Letters Patent is:

1. In a builder motion, the combination with a ring rail, of builder mechanism for giving traverse to the ring rail and including a builder chain, and means to actuate 30 the latter, bunch-building mechanism comprising a loop-forming element over which the chain passes and which forms a loop therein, and means for moving said element bodily thereby to lengthen and shorten 35 the loop of the chain to produce a short traverse in the ring-rail for the formation of a bunch.

2. In a builder motion, the combination with a ring rail, of builder mechanism for 40 giving traverse to the ring rail and including a builder chain and means to actuate the latter, bunch-building mechanism comprising means forming a loop in the chain, means for causing a lengthening and 45 shortening of the loop thereby to produce a short traverse in the ring rail for the formation of the bunch, and means to render the bunch-building mechanism inoperative after the bunch has been wound.

50 3. In a builder motion, the combination with a ring rail, of builder mechanism for giving traverse to the ring rail and including a builder chain and means to actuate the latter, bunch-building mechanism comprising means forming a loop in the chain, means for causing a lengthening and shortening of the loop thereby to produce a short 55 traverse in the ring rail for the formation of the bunch, and automatic means to render the bunch-building mechanism inoperative after the bunch has been wound.

4. In a device of the class described, the combination with a ring rail, of builder mechanism for giving traverse to the ring rail, said mechanism including a builder 60

chain and means to actuate the latter, bunch-building mechanism comprising a loop-forming element over which the chain passes and which forms a loop therein, and means actuated by the movement of the 70 chain for giving said element a bodily movement thereby to produce a short traverse in the ring rail for the formation of the bunch.

5. In a device of the class described, the 75 combination with a ring rail, of builder mechanism for giving traverse to the ring rail, said mechanism including a builder chain and means to actuate it, and bunch-building mechanism comprising a loop- 80 forming element over which the chain passes and which forms a loop therein, and means for moving said element bodily in one direction to lengthen the loop as the ring-rail moves in one direction and for moving said 85 element bodily in the opposite direction to shorten the loop when the ring-rail moves in the opposite direction.

6. In a device of the class described, the combination with a ring rail, of means for 90 giving said ring rail a traversing movement, said means including a builder chain and bunch-building mechanism comprising means for forming in the builder chain a loop having a fixed transverse dimension, 95 and a bunch-building cam for varying the length of the loop as the ring rail rises and falls whereby a portion of the motion given to the builder chain is absorbed in the loop.

7. In a device of the class described, the 100 combination with a ring rail, of means for giving said ring rail a traversing movement, said means including a builder chain and bunch-building mechanism comprising means for forming in the chain a loop hav- 105 ing a fixed transverse dimension, a bunch-building cam for varying the length of the loop as the ring rail rises and falls whereby a portion of the motion given to the builder chain is absorbed in the loop, and means to 110 actuate said cam by movement of the chain.

8. In a device of the class described, the combination with a ring rail, of a builder chain associated therewith for giving a rising and falling movement thereto, and 115 bunch-building mechanism comprising a sprocket wheel engaging the chain and forming a loop therein and means to move said sprocket wheel bodily in a direction to lengthen or shorten the loop whereby a portion of the motion given to the builder chain 120 is absorbed in the loop.

9. In a device of the class described, the combination with a ring rail, of a builder chain associated therewith for giving a rising and falling movement thereto, and bunch-building mechanism comprising a sprocket wheel engaging the chain and forming a loop therein, a movable member 125 on which said sprocket wheel is rotatably 130

mounted, and means to move said member thereby to lengthen and shorten the loop.

10. In a device of the class described, the combination with a ring rail, of a builder chain associated therewith for giving a rising and falling movement thereto, and bunch-building mechanism comprising a sprocket wheel engaging the chain and forming a loop therein, a swinging frame

5 on which said sprocket wheel is rotatably mounted, and means to swing said frame thereby to lengthen or shorten the loop.

11. In a device of the class described, the combination with a ring rail, of a builder chain associated therewith for giving a rising and falling movement thereto, and bunch-building mechanism comprising a sprocket wheel engaging the chain and forming a loop therein, a movable member

15 on which said sprocket wheel is rotatably mounted, and means actuated by the chain to move said member thereby to lengthen and shorten the loop.

12. In a device of the class described, the combination with a ring rail, of a builder chain associated therewith for giving a rising and falling movement thereto, and bunch-building mechanism comprising a sprocket wheel engaging the chain and forming a loop therein, a swinging frame on which said sprocket wheel is rotatably mounted, and means actuated by the chain to swing said frame thereby to lengthen or shorten the loop.

13. In a device of the class described, the combination with a ring rail, of a builder chain associated therewith for giving a rising and falling movement thereto, and bunch-building mechanism comprising a sprocket wheel engaging the chain and forming a loop therein, a movable member

40 on which said sprocket wheel is rotatably mounted, and a bunch-building cam to move said member thereby to lengthen or

45 shorten the loop.

14. In a device of the class described, the combination with a ring rail, of a builder chain associated therewith for giving a rising and falling movement thereto, and bunch-building mechanism comprising a sprocket wheel engaging the chain and forming a loop therein, a movable member

50 on which said sprocket wheel is rotatably mounted, and a bunch-building cam actuated by the builder chain to move said member thereby to lengthen and shorten the loop.

15. In a device of the class described, the combination with a ring rail, of a builder chain associated therewith for giving a rising and falling movement thereto, and bunch-building mechanism comprising a sprocket wheel engaging the chain and forming a loop therein, a swinging frame on

65 which said sprocket wheel is rotatably

mounted, and a bunch-building cam actuated by the builder chain to swing said frame thereby to lengthen or shorten the loop in the builder chain.

16. In a device of the class described, the combination with a ring rail, of a builder chain operatively connected thereto, means for giving the builder chain a reciprocating movement, and bunch-building mechanism comprising a sprocket wheel engaging said chain and forming a loop therein, a bunch-building cam associated with the sprocket wheel, and an abutment against which said cam acts whereby the movement of the bunch-building cam relative to the abutment caused by the reciprocating movement of the builder chain operates to lengthen and shorten the loop.

17. In a device of the class described, the combination with a ring rail, of a builder chain for giving traverse to the latter, a frame, two direction pulleys over which the builder chain passes, a swinging member carried by the frame, a sprocket wheel rotatably mounted on said swinging member and engaging the portion of the chain between said direction pulleys thereby to form a loop in the chain, and means to move said swinging member relative to the frame thereby to vary the length of the loop.

18. In a device of the class described, the combination with a ring rail, of a builder chain for giving traverse to the latter, a frame, two direction pulleys over which the builder chain passes, a swinging member

100 carried by the frame, a sprocket wheel rotatably mounted on said swinging member and

engaging the portion of the chain between

said direction pulleys thereby to form a loop

105 in the chain, and means operated by the movement of the chain to move said swinging member relative to the frame thereby to vary the length of the loop.

19. In a device of the class described, the combination with a ring rail, of a builder chain for giving traverse to the latter, a frame, two direction pulleys over which the builder chain passes, a swinging member carried by the frame, a sprocket wheel rotatably mounted on said swinging member and

engaging the portion of the chain between

said direction pulleys thereby to form a loop

110 in the chain, and means operated by movement of the chain in one direction to move

the swinging member relative to the frame

115 in a direction to elongate the loop, movement of the chain in the other direction operating

120 to shorten the loop.

20. In a device of the class described, the combination with a ring rail, of a builder chain operatively connected thereto, means for giving the builder chain a reciprocating movement, and bunch-building mechanism comprising an oscillatory member about

125 which the builder chain passes which forms

130

- a loop therein and which is oscillated by the movement thereof, a bunch-building cam associated with said oscillatory member, an abutment against which said cam acts as said member is oscillated thereby to cause a bodily movement of the latter which results in a lengthening and shortening of the loop whereby the ring rail has a short traverse to effect the winding of a bunch on a yarn receiver, and means to render said cam inoperative after the bunch has been formed whereby the ring rail is given longer traverse to effect the laying of a main or service winding.
- 5 21. In a device of the class described, the combination with a ring rail, of a builder chain operatively connected thereto, means for giving the builder chain reciprocating movement, and bunch-building mechanism comprising a sprocket wheel engaging said chain and forming a loop therein, a swinging bunch-building cam associated with the sprocket wheel, an abutment coöperating with said cam to effect a lengthening and 10 shortening of said loop as the chain reciprocates whereby a short traverse is given to the ring rail for the formation of a bunch on a yarn receiver.
- 15 22. In a device of the class described, the combination with a ring rail, of a builder chain operatively connected thereto, means for giving the builder chain reciprocating movement, and bunch-building mechanism comprising a sprocket wheel engaging said 20 chain and forming a loop therein, a swinging bunch-building cam associated with the sprocket wheel, an abutment coöperating with said cam to effect a lengthening and shortening of said loop as the chain reciprocates whereby a short traverse is given to the ring rail for the formation of a bunch on a yarn receiver, and means to move said cam progressively into a position where its engagement with the abutment will render it inoperative after the bunch has been laid thereby to provide for the laying of a main or service winding.
- 25 23. In a device of the class described, the combination with a ring rail, of a builder chain operatively connected thereto, means for giving the builder chain a reciprocating movement, a sprocket wheel engaging said chain and forming a loop therein, a bunch-building cam associated with the sprocket wheel and movable from its operative to its inoperative position, an abutment against which said cam acts when in its operative position thereby to effect a lengthening and shortening of the loop as the builder chain reciprocates; thereby to effect a preliminary winding on a yarn receiver with a short traverse, and means actuated by the reciprocation of the builder chain to move the builder cam into a position where it will be rendered inoperative when said preliminary 30
- winding has been laid, whereby the ring rail will be given longer traverse for laying a service or main winding.
24. In a device of the class described, the combination with a ring rail, of a builder chain for giving traverse thereto, a frame, a swinging member carried by the frame, a sprocket rotatably mounted on said swinging member and engaging said chain thereby to form a loop therein, means operated by the movement of the chain to give said swinging member a movement which produces lengthening and shortening of said loop whereby the ring rail is given a short traverse to effect the laying of a preliminary winding, and means to hold said swinging member in stationary position during the laying of the main or service winding.
- 35 25. In a device of the class described, the combination with a ring rail, of a builder chain for giving traverse thereto, a sprocket wheel around which the chain passes and which forms a loop therein, a movable member on which said sprocket wheel is rotatably mounted, means associated with the sprocket wheel for moving said movable member bodily as the chain reciprocates, thereby to lengthen and shorten the loop and thus produce a short traverse in the ring rail, to effect the laying of a preliminary winding or bunch on a yarn receiver, and means to hold said movable member stationary during the laying of the main or service winding on said yarn receiver.
- 40 26. In a device of the class described, the combination with a ring rail, of a builder chain for giving traverse thereto, a sprocket wheel around which the chain passes and which forms a loop therein, a movable member on which said sprocket wheel is rotatably mounted, a bunch-building cam associated with the sprocket wheel for moving said movable member bodily as the chain reciprocates, thereby to lengthen and shorten the loop and thus produce a short traverse in the ring rail to effect the laying of a preliminary winding or bunch on a yarn receiver, means to move said cam progressively into a position where its engagement with the abutment will render it inoperative after the bunch has been laid, means to hold said movable member stationary during the laying of the main or service winding on said yarn receiver, and means for returning said cam to its operative position after the main or service winding has been laid.
- 45 27. In a device of the class described, the combination with a reciprocating ring rail, of means to reciprocate it, and means to control its reciprocation to effect a preliminary winding of yarn upon a yarn receiver with a short traverse, a main or service winding on said yarn receiver with a longer 50

traverse and a final winding on said yarn receiver with a short traverse.

28. In a device of the class described, the combination with a reciprocating ring rail, of means to reciprocate it, and means to control its reciprocation to effect three successive windings on a yarn receiver, the first and third of which have a shorter traverse than the intermediate winding, which constitutes a main or service winding.

29. In a device of the class described, the combination with a ring rail, of means to reciprocate it, and means to control its reciprocation to effect the laying of first a main or service winding on a yarn receiver and subsequently a final winding having a shorter traverse than the main winding.

30. In a device of the class described, the combination with a ring rail, of a builder chain operatively connected thereto, means forming a loop in said chain, means for giving the chain a to and fro movement thereby to give the ring rail its reciprocating movement to lay a main or service winding on a yarn receiver, and means rendered operative when the service winding is laid to effect a lengthening and shortening of the loop as the chain reciprocates whereby a final winding is laid on the yarn receiver with a short traverse.

31. In a device of the class described, the combination with a ring rail, of a builder chain operatively connected thereto, means for giving the builder chain to and fro movement thereby to reciprocate the ring rail to effect the formation of a main or service winding on a yarn receiver and means rendered operative when said service winding is completed to absorb in the chain a part of the movement given thereto whereby a final winding of short traverse is laid on the yarn receiver.

32. In a device of the class described, the combination with a ring rail, of a builder chain operatively connected thereto, means to give the builder chain a to and fro movement to produce a reciprocation of the ring rail and means to absorb in said builder chain a portion of the movement given thereto during the laying of both the initial and final winding on a yarn receiver whereby such initial and final winding will be laid with a short traverse, said means being inoperative during the laying of the intermediate or service winding.

33. In a device of the class described, the combination with a ring rail, of means for reciprocating said ring rail to effect the laying of a main or service winding on a yarn receiver and means for effecting the laying of a final winding on said yarn receiver with a different length of traverse than that of the main winding.

34. In a device of the class described, the combination with a ring rail, of means for

reciprocating said ring rail to effect the laying of a main or service winding on a yarn receiver and means for effecting the laying of a final winding on said yarn receiver with a shorter length of traverse than that of the main winding.

35. In a device of the class described, the combination with means for supporting a bobbin, of a ring rail, builder mechanism for giving traverse to the ring rail to lay a main or service winding on a bobbin and means to reduce the length of traverse of the ring rail when winding on the tip of the bobbin, thereby to produce a final winding with a short traverse.

36. In a device of the class described, the combination with a ring rail, of an oscillating member connected thereto, a continuous builder chain operatively connected to said member, means for actuating the chain, and means situated intermediate of the ends of the chain at a point separated from the oscillating member but not affecting the continuity of the chain and actuated by the movement of said chain to effect the formation of two successive windings on a yarn receiver constituting bunch and service windings, respectively.

37. In a device of the class described, the combination with a ring rail, of a builder chain operatively connected thereto, means for actuating the builder chain, and means situated intermediate of the ends of said chain and actuated by movement thereof to effect the formation of three successive windings on a yarn receiver constituting preliminary service, and final windings respectively.

38. In a builder motion, the combination with a ring-rail, of builder mechanism for giving traverse to the ring-rail and including a builder chain, and means to actuate the latter, bunch-building mechanism comprising means operative in all positions of the ring-rail to form a loop in the chain, and means for causing a lengthening and shortening of the loop thereby to produce a short traverse in the ring-rail for the formation of the bunch.

39. In a builder motion, the combination with a ring-rail, of builder mechanism for giving traverse to the ring-rail and including a builder chain and means to actuate it, bunch-building mechanism comprising a loop-forming member over which the chain passes and which forms a loop therein in all positions of the ring-rail, and means for actuating said member to lengthen and shorten the loop thereby to produce a short traverse in the ring rail for the formation of a bunch.

40. In a device of the class described, the combination with a ring-rail, of a rocking member connected thereto, a builder arm, means for actuating the latter, a continuous

chain connecting the builder arm to the rocking member, and means situated between said rocking member and said arm and coöperating with the chain to absorb 5 a part of the movement given to said chain by the builder arm during the laying of the initial winding on a yarn receiver.

In testimony whereof, I have signed my name to this specification, in the presence of two subscribing witnesses.

LOUIS S. BURBANK.

Witnesses:

DANA OSGOOD,
FRED R. DANIELS.

Copies of this patent may be obtained for five cents each, by addressing the "Commissioner of Patents, Washington, D. C."

It is hereby certified that in Letters Patent No. 1,125,924, granted January 26, 1915, upon the application of Louis S. Burbank, of Hopedale, Massachusetts, for an improvement in "Traverse-Motions for Yarn-Spinning Apparatus," an error appears in the printed specification requiring correction as follows: Page 10, line 102, after the word "preliminary" insert a comma; and that the said Letters Patent should be read with this correction therein that the same may conform to the record of the case in the Patent Office.

Signed and sealed this 9th day of February, A. D., 1915.

[SEAL.]

J. T. NEWTON,

Acting Commissioner of Patents.
